[57] **CLAIM**

The ornamental design for a toy loader with pivotable shovel and removable nested components, as shown and described.

DESCRIPTION

FIG. 1 is a front, top and left side perspective view of a toy loader with pivotable shovel and removable nested components showing our new design; FIG. 2 is a rear, top and left side perspective view thereof;

FIG. 3 is a top perspective view thereof;

FIG. 4 is a bottom perspective view thereof;

FIG. 5 is a front perspective view thereof;

FIG. 6 is a left side perspective view thereof;

FIG. 7 is a rear, top and right side perspective view thereof with the shovel in forward, raised position; and FIG. 8 is a rear, top and right side perspective thereof with the shovel in a raised rearward position and the nested components in an exploded condition.
